ARCHIBALD D. EVANS, OF WARREN, OHIO, ASSIGNOR TO THE WEAN ENGINEERING COMPANY, INC., OF WARREN, OHIO, A CORPORATION OF OHIO

COATING MACHINE DRIVE

Application filed July 14, 1930. Serial No. 467,851.

This invention relates to coating machine drives and is described herein as applied to galvanizing machines, although the drive may be used in connection with other types of coating machines.

In the accompanying drawings, which illustrate the present preferred embodiment of my invention—

Figure 1 is a plan view of a galvanizing machine and a drive embodying my invention;

Figure 2 is a longitudinal sectional view of the machine shown in Figure 1;

Figure 3 is an enlarged plan view of the galvanizing machine drive; and

Figure 4 is an enlarged sectional view through the galvanizing kettle showing the means for driving the center rolls.

In carrying out a galvanizing process it is usual to pass the sheets after they have been washed through squeegee rolls to remove the water and then to pass them in succession between entrance or flux rolls, center rolls, and final coating rolls, after which they are deposited on a conveyor which leads them to straightening machines.

The uniform coating of the sheets depends largely upon the efficient operation of the exit or final coating rolls. These rolls become pitted after they have been used for some time and in order to provide a smooth surface thereon they are machined or dressed at frequent intervals. The dressing of the exit rolls reduces them in diameter and it accordingly becomes necessary to change the revolution speed of the exit rolls, or the revolution speed of the entrance and center rolls in order that the peripheral speed of all of these sets of rolls may be the same.

It has been customary heretofore to change the speed of revolution of the exit rolls after they have been dressed in order to compensate for the decrease in diameter. Changing the revolution speed of the exit rolls necessitates the use of a change speed device between the driving motor or other prime mover and the exit rolls. The use of a change speed unit between the driving motor and the exit rolls is objectionable for the reason that wherever a change speed unit is em-

ployed it results in chatter and vibration, which is transmitted at least in part to the final exit rolls. As previously stated, the character and uniformity of the coating is largely determined by the vibration and chatter in the exit rolls, so that in order to produce uniform coating of the sheets it is necessary that the exit rolls be free from vibration and chatter. A small amount of vibration in the entrance or center rolls does not have nearly as bad an effect on the coating as if the vibration were in the exit rolls.

In accordance with the present invention, vibration and chatter of the exit rolls is eliminated or substantially decreased by the elimination of all change speed gearing between the prime mover and the exit rolls, the speed ratio of the driving motor and the exit rolls always being maintained constant. In order to provide the desired speed of exit rolls, a worm reduction unit is used in the connection between the motor and the exit rolls. It is necessary, however, to change the revolution speeds of the entrance and center rolls in order to compensate for dressing down the exit rolls and this is accomplished in the present invention by providing a speed change unit between the driving motor and the entrance and center rolls. In accordance with the present invention, there is provided a constant speed ratio gearing between the driving motor and the exit rolls, and a variable speed ratio gearing between the driving motor and the entrance and center rolls. This provides a more uniform coating than could be obtained heretofore, since the vibration caused by the speed change gearing between the driving motor and the entrance and center rolls does not have as adverse an effect on the coating as would be caused by an equal amount of vibration transmitted to the exit rolls. The amount of vibration is also reduced by the use of gear transmissions having as a final drive unit just prior to the rolls a worm and worm wheel type gear.

Referring more particularly to the accompanying drawings, the pickled sheets which are stored in a water bosh 2 are fed manually through the squeegee rolls 3 and guides 4 to the entrance or flux rolls 5 and 5'. They are

guided from the entrance rolls 5 to the center rolls 6 and 6' by entrance guides 7 and are guided from the center rolls to the exit rolls 8 and 8' by exit guides 9. After passing between the exit rolls 8, they are delivered to a conveyor 10 on which they cool and which transports them to straightening devices, not shown.

The squeegee rolls 3 are driven from a driven shaft 20, as shown in Figure 1, through a sprocket chain 21 and sprocket wheels 22 and 23 connected respectively to the shaft 20 and a shaft 24 connected to one of the rolls 3. The upper squeegee roll 3 is resiliently pressed into contact with the lower roll by a spring 25, as indicated in Figure 4.

The entrance rolls 5 and 5' are also driven from the shaft 20, which is connected through a clutch 27 to a shaft 28 having a gear 29 secured thereto. The gear 29 meshes with a gear 30 carried by the neck of the roll 5'. The roll 5' is forced toward the roll 5 by a spring 30', as shown in Figure 4.

The lower center roll 6 is provided at one end with a worm wheel 35 which is driven by a worm 36 on a vertically extending shaft 37 mounted in bearings 38 and 39. The shaft 37 carries at its upper end a bevel gear 40 which meshes with a bevel gear 41 which is secured to a driven shaft 42. The upper center roll 6' is driven from the lower center roll 6 through pinions on the opposite end of the roll necks. The upper roll 6' is mounted in a movable bearing 45 which has a rod 46 connected thereto. The upper end of the rod 46 is connected at 47 to an arm 48 pivoted at 49 and provided with a weight 50 which urges the bearing 45 and upper roll 6' toward the lower center roll 6.

The exit roll 8' is driven from a shaft 60 by means of a gear 61 secured to the shaft and a gear 62 secured to the roll 8'. The roll 8 is driven from the roll 8' by means of pinions 63 and 64 on the opposite roll necks. The roll 8' is forced toward the roll 8 by a spring 65 surrounding a link 66 and abutting against a washer 67 and a bracket 68. The spring 65 has a tendency to rotate an arm 69 about its pivot 69', thereby forcing the lower end of the arm against the neck of the roll 8' to force it toward the roll 8.

The drive for the various rolls is shown in detail in Figure 3. The rolls 8 and 8' are driven from a motor 70 having a worm reduction unit 71 connected to the right-hand end of the motor armature shaft 72 by a flexible coupling 73. The worm reduction unit 71 drives the shaft 60 which is mounted in bearings 75 through a flexible coupling 76. The final transmission gear 61 is carried by the shaft 60 on the end nearest the galvanizing machine, the gear 61 operating the exit rolls 8 and 8' as previously described. It will be seen that the only gearing between the driving motor 70 and the exit rolls 8 and 8' is the

worm reduction unit 71 and that no speed change unit is used between the motor and the exit rolls. This eliminates any vibration or chatter of the exit rolls, which would necessarily be introduced if a speed change unit were employed in the connection between the driving motor and the exit rolls.

In order to adjust the speed of revolution of the center rolls 6 and 6' and the entrance rolls 5 and 5' so as to make their peripheral speeds correspond to the peripheral speed of the exit rolls 8 and 8' after they have been dressed, a speed change unit 80a is introduced into the gearing between the driving motor 70 and the entrance and center rolls. As shown in Figure 3, the left-hand end of the motor armature shaft 72 is connected by a flexible coupling 73 to a shaft 74 of the speed change unit. Mounted loosely on the shaft 74 are four gears, 75, 76, 77 and 78, the diameter of the gears decreasing in the order named. Clutches 79 and 80 are keyed to the shaft 74 and may be optionally engaged with the gears 75, 76, 77 and 78. Gears 81, 82, 83 and 84, which decrease in diameter in the order named, are secured to a shaft 85. Gears 86, 87, 88 and 89, which increase in diameter in the order named, are mounted loosely on a shaft 90 in a manner similar to the gears 75, 76, 77 and 78. Clutches 91 and 92 are keyed to the shaft 90 and are slideable so that the clutch 91 may optionally engage either of the gears 88 or 89 and the clutch 92 may optionally engage either of the gears 86 or 87. The arrangement of gears in the speed change unit 80a is such that sixteen speed changes may be effected so as to compensate for sixteen dressings of the exit rolls 8 and 8', each of which dressings ordinarily reduces the diameter of the exit rolls one sixteenth of an inch.

The shaft 90 is connected by a flexible coupling 91a to a second worm reduction unit 92a, which in turn is connected by a flexible coupling 93 to a mitre gear unit 94. The mitre gear unit 94 drives the shaft 42 to which the bevel gear 41 is secured, the bevel gear 41 driving the center rolls 6 and 6', as previously described. The mitre gear unit 94 is connected by shafts 95 and 96 and flexible couplings 97 to a third worm reduction unit 98 which drives the shaft 20 and through the clutch 27 drives the entrance rolls 5 and 5'.

There are various kinds of speed changing units which might be used in place of the speed change unit 80a hereinabove described. For example, a standard link belt infinitely variable speed transmission might be used in place of the speed change unit 80a, the particular type of speed change unit depending upon the particular circumstances. The present invention contemplates the use of any suitable type of speed change device in the gearing between the driving motor and the entrance and center rolls of the galvanizing

machine in order to compensate for dressing the exit rolls. However, the exit rolls are always driven by gearing which is free from any speed change unit which, if used, would cause vibration and chattering of the exit rolls. The only gearing between the driving motor 70 and the exit rolls 8 and 8', in the embodiment above described, is a worm reduction unit which does not cause vibration of the exit rolls. The arrangement of the gear transmissions, as herein described, results in a drive which is substantially free from vibration or chattering of the exit rolls and which accordingly deposits an even coating on the sheets which are being treated.

I have illustrated and described the present preferred embodiment of my invention. It is to be understood, however, that the invention may be otherwise embodied within the scope of the following claims.

I claim:

1. A drive for coating machines having entrance, center, and exit rolls, comprising a prime mover, a speed change unit operatively connecting the entrance and center rolls with the prime mover, and constant speed ratio gearing connecting the prime mover and exit rolls.

2. A drive for coating machines having entrance, center, and exit rolls, comprising a prime mover, constant speed ratio gearing connecting the prime mover and exit rolls, and change speed gearing connecting the entrance and middle rolls with the prime mover, whereby the speed of revolution of the entrance and center rolls may be adjusted to compensate for dressing the exit rolls.

3. In a drive for coating machines having entrance, center, and exit rolls, a prime mover, and gear transmission between the prime mover and exit rolls, said transmission including a worm reduction unit but being free of speed change devices.

4. A drive for coating machines having entrance, center, and exit rolls, which comprises a prime mover, a constant speed ratio gearing including a worm reduction unit operatively connecting the prime mover and exit rolls, and change speed gearing connecting the prime mover with the entrance and center rolls.

5. A drive for coating machines having entrance, center, and exit rolls, which comprises a motor, a worm reduction unit directly connected thereto, a shaft driven by the worm reduction unit, said shaft being provided with a final transmission gear adapted to rotate the exit rolls, and change speed gearing connecting the motor with the entrance and center rolls.

6. A drive for coating machines having entrance, center, and exit rolls, which comprises a motor, a worm reduction unit connected to one end of the motor armature shaft, a shaft driven by the worm reduction unit and opera-

tively connected to the final exit rolls, a speed change unit connected to the opposite end of the motor armature shaft, and operative connections between the speed change unit and the entrance and center rolls.

7. A drive for coating machines having entrance, center, and exit rolls, which comprises a motor, a worm reduction unit connected to one end of the motor armature shaft, a shaft driven by the worm reduction unit and operatively connected to the final exit rolls, a speed change unit connected to the opposite end of the motor armature shaft, and gear transmissions connecting the speed change unit with the entrance and center rolls, each of the gear transmissions having as a final drive unit just prior to the rolls a worm and worm wheel type gear.

8. A drive for coating machines having entrance, center, and exit rolls, which comprises a motor, a worm reduction unit connected to one end of the motor armature shaft, a shaft driven by the worm reduction unit and operatively connected to the final exit rolls, a speed change unit connected to the opposite end of the motor armature shaft, a second worm reduction unit connected to the speed change unit, a miter gear unit connected to said second worm reduction unit, a third worm reduction unit connected to said miter gear unit, said third worm reduction unit and miter gear unit being adapted to drive the entrance and center rolls.

9. A drive for coating machines having entrance, center and exit rolls, which comprises a motor, a worm reduction unit connected thereto, a final transmission gear adapted to rotate the exit rolls, said final transmission gear being driven through said worm reduction unit, the drive for the exit rolls being free of speed change devices, and a speed change unit in the drive for the entrance and center rolls.

In testimony whereof I have hereunto set my hand.

ARCHIBALD D. EVANS.
